W. T. CROSLIN.
STOVE.
FILED Oct. 26, 1921.

Inventor:
William T. Croslen
By John C. Higdon
Attorney

UNITED STATES PATENT OFFICE.

WILLIAM THOMAS CROSLIN, OF SPRINGFIELD, MISSOURI.

STOVE.

Application filed October 26, 1921. Serial No. 510,589.

To all whom it may concern:

Be it known that I, WILLIAM T. CROSLIN, a citizen of the United States, residing at Springfield, in the county of Greene, State 5 of Missouri, have invented certain new and useful Improvements in Stoves, of which the following is a specification, containing a full, clear, and exact description, reference being had to the accompanying drawing, 10 forming a part hereof.

My invention consists in the novel disclosure hereinafter particularly described and distinctly claimed.

The object of my invention is to provide 15 an improved device for burning fuel (especially soft coal), which may be readily applied to heating-stoves, furnaces, water-heaters, ranges and other fuel-burning apparatus; whereby the fuel will be very eco- 20 nomically consumed, soot and smoke will be prevented, and a blue flame will be produced in the combustion-chambers of the stove or other fuel-burning apparatus.

In the drawing, 25 Fig. 1 is a vertical section of one form of heating-stove, having my invention embodied therein, and

Fig. 2 is a fragmentary plan-view of the top of the stove and adjacent parts, with 30 the outer perforated cover detached.

The numeral 1 designates the outer casing of the stove or other heating-apparatus, provided with any suitable form of ash-pan 2, grate 3 and smoke-pipe 4.

An outer cover 5 has a series of air-inlets 35 or perforations 30, and is detachably (or movably) mounted over a central opening, formed in the horizontal top-plate 19.

A fire-box 6 is located in the lower portion 40 of the stove or other fuel-burning apparatus, and a narrow annular combustion-chamber 7 is formed between the upper vertical wall of said fire-box and the adjacent outer cylindrical casing 12, which projects downwardly 45 into said fire-box a considerable distance.

Said vertical wall of said fire-box 6 is provided with numerous small holes or perforations 8, which act as air-ducts, and supply the said annular combustion-chamber 7 50 with fresh air, at a point above the fuel that is burning on said grate 3, and at points di-

rectly opposite small air-ducts or holes 14 which are formed in the adjacent vertical wall of said casing 12.

A fuel magazine 11 is located within said 55 casing 12, so as to form an annular hot-air space 10 between said magazine and said casing, the lower ends of the latter and the magazine being joined by a ring-like head, through the large central opening of which 60 the soft-coal or other fuel may freely pass from said magazine directly into the lower part of the said fire-box 6, and be thereat supported by the said grate 3.

A horizontal partition 9 is located within 65 the said outer casing 1 of the stove or other fuel-burning apparatus, at a point sufficiently elevated to support the said fire-box 6, which is preferably (as shown) made integral with said partition; said partition being fixed to the said outer casing, in any desired workman-like manner, so that all 70 passage of air from the space below said partition to the space above the same must take place through the said fire-box air- 75 ducts 8, and through the fuel in the lower part of said fire-box.

Suitable L-shaped supporting-brackets 15 extend radially from the said partition 9 to the adjacent outer wall 12 of the annular 80 hot-air space 10, to support said wall and the fuel magazine 11, and hold them in proper relation to the said fire-box 6 and the annular combustion-chamber 7; suitable rivets or other fastening-means being used, as 85 shown, to fasten said brackets to said partition and to said outer wall 12.

A fire-door 24 is connected to the interior of the said fire-box 6 by a common fire-door throat 25, to afford access to the interior of 90 the fire-box, in starting a fire, and in cleaning out the fire-box when the grate 3 is not of the dumping form.

A cold-air inlet opening 28 is made in the said outer casing 1 of the apparatus, to supply cold air to the space below the said horizontal partition 9, and a common handled-slide or register 29 is arranged to control the passage of air through the said cold-air inlet opening. The lower end of the said 100 hot-air chamber 10 projects centrally down into the said annular combustion-chamber 7.

A ring-like head having a series of small air-inlets or openings 16, connects the upper adjacent ends of the said fuel magazine 11, and a ring-like register-plate 17 is provided with a series of small air-openings 20, and is rotatably mounted upon the said head in such a manner that the air-openings 20 of said register-plate will register with said air-inlets 16 of said head 10 when it is desired to permit air to pass into the upper end of the said annular hot-air space 10.

When it is desired to cut off, or decrease, the entrance of air to the said upper end 15 of said annular hot-air space the said register-plate is moved accordingly, to a position where said air-inlets 16 of said head of the hot-air space will be more or less obstructed by an imperforate part of said register-plate.

An L-shaped handle 18 is attached to or formed integral with the outer marginal edge of the said register-plate 17, and extends to the exterior of the top-plate 19 of 25 the stove through a slot 18^a which is formed therein; whereby the said register-plate may be set as required for the most economical operation.

An inner cover 21 is detachably mounted 30 upon the said register-plate 17, and is provided with a cold-air opening 22, through which air is admitted to the upper end of the said fuel-magazine 11, to keep cool the fuel that is contained in the latter, and 35 thereby assure its certain movement toward the fire-box 6, as wanted.

A hinged slide 23 is mounted upon said inner magazine-cover 21, over the said cold-air opening 22 thereof, to control the entrance of air therat, as required for the most successful operation.

An annular flange 26 depends from the underside of said top-plate 19, and the upper end of the outer wall 12 of said hot-air space 10 is secured thereto by means of 45 rivets or other fastenings; thereby bracing and supporting the upper ends of said hot-air space and said fuel magazine.

I do not confine myself to any specific 50 materials, as those skilled in the art of stove manufacturing will readily select the most efficient material for each part of the apparatus; nor do I limit myself to the exact form or proportions of parts herein 55 shown, as it will be readily understood that such changes as readily suggest themselves to skilled mechanics may be made without departing from the spirit of my invention and the scope of my claim.

Upon lighting a fire in the fire-box 6, and supplying the magazine 11 with fuel (say soft coal), the following operations 60 will take place:

The said smoke-pipe, if connected to a 65 suitable chimney or other suction-producing

apparatus, will create a partial vacuum within the outer casing 1, above the said horizontal partition 9.

Then, upon opening the cold-air slide 29 a supply of air will enter the space below 70 said horizontal partition 9, and part of said air will pass upwardly through the fuel on the grate 3, and the fuel on the latter will be burned, and the smoke and products of such primary combustion will pass into the 75 said annular combustion-chamber 7, wherein it simultaneously meets and is subjected to the action of the numerous small opposite jets of air issuing from the opposite perforations or ducts 8 of the vertical wall 80 of said fire-box, and the ducts 14 of the closely adjacent vertical wall 12 of the annular hot-air space 10; which will cause all of the smoke and other combustible products of the said primary combustion on said 85 grate, to burn with an intensely-hot blue flame, in the upper part of said annular combustion-chamber 7, as well as directly above the same in the main heating space of the apparatus above the said horizontal 90 partition.

Said blue flame will, of course, heat the outer casing 1, or other substitute therefor, to a degree depending upon the quantity of fuel consumed in a given time. 95

Said blue flame will also, of course, heat the outer wall 12 of the said annular hot-air chamber 10, so that the supply of hot air for the previously-mentioned hot-air ducts 14 will be ample and satisfactory, if 100 the said hot-air register-plate is set to permit a sufficient supply of cold air to flow into said hot-air chamber 10 by way of the said registering air-openings 16 and 20 at the upper end of said hot-air chamber. 105

Said outer wall 12 of the hot-air chamber 10 protects the fuel-magazine 11 from the extreme heat of the blue smokeless flame which surrounds said outer wall and said magazine.

I claim:—

In a stove, an outer casing; a fire-box having a series of air-ducts formed in its upper portion, a horizontal partition which separates the interior of the said casing into a portion above said fire-box and a portion in which the latter is located, an annular hot-air chamber having a series of hot-air ducts formed in its lower portion, which projects downwardly into said fire-box such 115 a distance that the hot-air ducts of said hot-air chamber are located and arranged to discharge directly opposite the air-ducts of said fire-box, an annular combustion-chamber surrounding the lower portion of 120 said hot-air chamber, and the walls of said fire-box surrounding said annular combustion-chamber, so that the jets of air from the air-ducts of both fire-box and hot-air chamber will meet and commingle with the 125 130

products of combustion that pass from said fire-box into said annular combustion-chamber; a fuel-magazine surrounded by the said annular hot-air chamber; means for regulating and supplying cold air to the upper end of said hot-air chamber; means for supplying and regulating air at the upper end of said magazine; and means for regulating the entrance of air to the fire-box through the grate thereof, and through the 10 said air-ducts thereof.

In testimony whereof, I have signed my name to this specification in presence of two subscribing witnesses.

WILLIAM THOMAS CROSLIN.
